Primary Examiner — Jennifer Rivard*Assistant Examiner* — Jennylo M Binas(74) *Attorney, Agent, or Firm* — Elevated IP, LLC(57) **CLAIM**

The ornamental design for an ultrasonic cleaning device, as shown and described.

DESCRIPTION

FIG. 1 is a back perspective view of an ornamental design for an ultrasonic cleaning device;

FIG. 2 is a front perspective view thereof;

FIG. 3 is a back view thereof;

FIG. 4 is a right side view thereof, the left side view being a mirror image of the right side view;

FIG. 5 is a top view thereof; and,

FIG. 6 is an expanded view thereof.

The broken lines shown in the figures are for the purpose of illustrating portions of the ultrasonic cleaning device and form no part of the claimed design. In addition, the bottom surface of the ultrasonic cleaning device, not shown, forms no part of the claimed design.
